(57) **CLAIM**

The ornamental design for a sump basin inlet connection, as shown and described.

DESCRIPTION

FIG. 1 is a front isometric view of a sump basin inlet connection showing my new design;

FIG. 2 is a top view of the sump basin inlet connection, a bottom view being a mirror image thereof;

FIG. 3 is a right side view of the sump basin inlet connection, a left side view being a mirror image thereof;

FIG. 4 is a front view of the sump basin inlet connection; and,

FIG. 5 is a rear view of the sump basin inlet connection.
